UNITED STATES PATENT OFFICE.

WILLIAM W. DODGE, OF MISHAWAKA, INDIANA, ASSIGNOR TO NATIONAL VENEER PRODUCTS COMPANY, OF MISHAWAKA, INDIANA, A CORPORATION OF INDIANA.

DESIGN FOR A BUTTERFLY GARMENT-RETAINER FOR WARDROBE-TRUNKS.

58,725.

Specification for Design.

Patented Aug. 30, 1921.

Application filed August 2, 1920. Serial No. 400,877. Term of patent 14 years.

To all whom it may concern:

Be it known that I, WILLIAM W. DODGE, a citizen of the United States, residing at Mishawaka, in the county of St. Joseph and State of Indiana, have invented a new, original and ornamental Design for a Butterfly Garment- Retainer for Wardrobe- Trunks, of which the following is a specification, reference being made to the accompanying drawing, forming a part thereof.

The design in its essential aspect comprises a garment retainer of ornate outline which simulates a butterfly with its wings outstretched.

The figure of the drawing is an elevation of a retainer, of which the fastenings are wholly incidental.

I claim:

The ornamental design for a butterfly garment retainer for wardrobe trunks, as shown.

WILLIAM W. DODGE.
